UNITED STATES PATENT OFFICE.

SARAH OSWALT, OF BRAZIL, INDIANA.

HANGER.

1,115,730.

Specification of Letters Patent. Patented Nov. 3, 1914.

Application filed September 15, 1911. Serial No. 649,472.

To all whom it may concern:

Be it known that I, SARAH OSWALT, a citizen of the United States, residing at Brazil, in the county of Clay and State of Indiana, have invented a new and useful Hanger, of which the following is a specification.

It is the object of this invention to provide a hanger comprising a bracket and a series of removable hook-members, the construction being such that the hook-members may readily be removed from the bracket, and, with equal facility, be inserted thereto, at the will of the operator.

A further object of the invention is to provide a hanger including a plurality of suspension elements which may be slid to and fro upon the supporting bracket, the construction being such that the number of suspension elements may be increased or diminished at will.

With the foregoing and other objects in view which will appear as the description proceeds, the invention resides in the combination and arrangement of parts and in the details of construction hereinafter described and claimed, it being understood that changes in the precise embodiment of invention herein disclosed can be made within the scope of what is claimed without departing from the spirit of the invention.

In the accompanying drawings,—Figure 1 shows the invention in side elevation, parts being broken away; Fig. 2 is a top plan, parts being broken away; Fig. 3 is a section on the line A—B of Fig. 1; and Fig. 4 is a side elevation, showing the device disposed in a different position from that depicted in Fig. 1.

In carrying out the invention there is provided a bracket 1, which is preferably fashioned from a flat bar of metal, and comprises an arm 2, from one end of which, a depending wall-plate 3 extends in which there are a number of openings 4, adapted to receive securing elements, whereby the bracket may be attached to a support. At its outer end, the arm 2 is upwardly and rearwardly curved, to form a stop or guard

5. In the arm 2 is a longitudinal slot 6, extending from a point 7' adjacent the wall-plate 3, through the stop 5 to the point 7. The structure further includes a plurality of suspension members, of which there may be any number consistent with the length of the arm 2 which may be increased at will.

The general outline of these suspension members is shown most clearly in Fig. 3.

In fashioning these suspension members, a pair of metallic strips are twisted together in their intermediate portions, to form the shank 8. The lower ends of the strips are curved outwardly and upwardly, to form the hook members 9. The upper ends of the strips are extended in opposite directions, in axial alinement, to form arms 10. The arms 10, the shank 8 and the hook 9 are located substantially in a common plane. The length of the arms 10, taken together, is substantially equal to the width of the arm 2, as clearly shown in Fig. 2, so that the ends of the arms 10 do not protrude beyond the outer edges of the arm 2. The width of the arms 10 is less than the width of the slot 6, the construction being such that when the arms 10 are alined with the slot 6, the arms may readily be passed therethrough, whereupon, if the suspension member be rotated, the arms 10 will be disposed transversely of the slot 6, to engage the upper face of the arm 2, upon both sides of the slot, as shown in Fig. 2. The shank 8 fits closely, yet slidably, in the slot 6, and it is obvious that the suspension member may be slid to and fro, from one end of the device toward the other. It is to be observed at this point that the upper end wall 11 of that portion of the slot 6 which extends into the stop 5, is spaced above the upper face of the arm 2, by a distance greater than the width of the arms 10. Ordinarily, the suspension members will be assembled with the bracket in the manner hereinbefore described, that is, by alining the arms 10 with the slot 6 and by passing them upwardly therethrough, the suspension members being again rotated, to dispose the arms 10 transversely of the slot 6, as shown in Fig. 2.

When the device is placed in a narrow closet, or in one which is dark, it is not always convenient to assemble the suspension members with the bracket, in the manner hereinbefore set forth. Under such circumstances, the suspension members may be passed inwardly, through the stop 5, the operation being as follows: The suspension members are rotated until the arms 10 are alined with the slot 6, whereupon the arms 10 pass inwardly, through the portion 7 of the slot 6, the suspension members being then rotated, so that the arms 10 will extend transversely of the slot 6. Owing to

the fact that the upper end wall 11 of the slot 6 is spaced from the upper face of the arm 2 of the bracket, by a distance greater than the width of the arms 10, it will not be necessary to lift the suspension members, after they have been passed inwardly through the portion 7 of the slot 6. The arms 10 ride along the slot, and when the end wall 11 has been passed, a mere rotation of the suspension member will be sufficient to hold it assembled with the bracket, as shown in Fig. 2. It will of course be understood that the stop 5 will serve to prevent articles which are hung directly upon the arm 2, from slipping off the said portion.

The device, generally considered, is so constructed that one hook after another may readily be mounted upon the bracket, the hooks being pushed backwardly and forwardly, as may be desired, to give access to the articles which the hooks carry.

There is a further advantage in extending the slot 6 through the stop 5, as shown in Fig. 1. If desired, the wall-plate 3, instead of being secured to the horizontal support, may be secured to an overhead support, the arm 2, under such circumstances, hanging vertically, as shown in Fig. 4. The suspension member will then slide down and hang

in a vertical position, the arms 10 being engaged across the stop 5. An article may then be hung upon the stop 5, other articles being engaged by the hooked portions 9 of the suspension members.

Having thus described the invention, what is claimed is:—

A hanger comprising a wall plate, a straight arm carried thereby and projecting horizontally therefrom, a hook-shaped terminal member at the free extremity of said arm and projecting thereabove, the extent of said hook member being relatively small with respect to the extent of said straight arm, said arm and terminal member provided with a longitudinal slot terminating adjacent the upper extremity of the hook-shaped terminal member, the slot of the terminal member adapted to receive the alined, laterally extending members of a hook therein, allowing the same, by a horizontal motion, to assume a position resting upon the arm.

In testimony that I claim the foregoing as my own, I have hereto affixed my signature in the presence of two witnesses.

MRS. SARAH OSWALT.
